UNITED STATES PATENT OFFICE.

BEREL McCACKEN AND CELESTER PIROTT, OF MOUNT PLEASANT, PENNSYLVANIA,
ASSIGNORS TO BRYCE BROTHERS COMPANY, OF MOUNT PLEASANT, PENNSYLVANIA,
A CORPORATION OF PENNSYLVANIA.

DESIGN FOR A GOBLET OR SIMILAR ARTICLE.

Application filed May 3, 1922. Serial No. 2,053. Term of patent 14 years.

To all whom it may concern:

Be it known that we, BEREL McCACKEN and CELESTER PIROTT, both citizens of the United States, residing at Mount Pleasant, in the county of Westmoreland and State of Pennsylvania, have invented a new, original, and ornamental Design for Goblet or Similar Article, of which the following is a specification, reference being had to the accompanying drawings, forming part thereof, in which—

Figure 1 is an elevation of a goblet embodying our new design; and

Figure 2 is a section on line II—II of Figure 1.

We claim:

The ornamental design for a goblet or similar article as shown.

In testimony whereof, we have hereunto set our hands.

BEREL McCACKEN.
CELESTER PIROTT.
